UNITED STATES PATENT OFFICE.

LEE H. KAUPKE, OF ROCK ISLAND, ILLINOIS, ASSIGNOR TO ROCK ISLAND PLOW COMPANY, OF ROCK ISLAND, ILLINOIS, A CORPORATION OF ILLINOIS.

QUICK-DETACHABLE PLOWSHARE.

1,356,723.

Specification of Letters Patent. Patented Oct. 26, 1920.

Application filed April 4, 1919. Serial No. 287,607.

To all whom it may concern:

Be it known that I, LEE H. KAUPKE, a citizen of the United States of America, and resident of Rock Island, Rock Island county, Illinois, have invented a certain new and useful Improvement in Quick-Detachable Plowshares, of which the following is a specification.

My invention relates to an improvement in quick detachable plow shares—that is, to improved means for readily connecting and disconnecting the plow share to and from the frog and mold-board. In operating in certain soils, the edge of the plow-share becomes dulled very quickly, thus necessitating the frequent changing of these shares. It is, therefore, advantageous to provide means whereby the share can be quickly and easily attached and detached from the mold-board instead of being secured thereto by the usual bolts or rivets. This is particularly true in connection with engine plows, in which it is difficult to tip the plow so as to gain ready access to the bottom of the plow, for the purpose of removing such bolts or rivets.

By my invention, I provide means by which the plow-share is firmly and securely held in position and can be detached from the mold-board without removing any bolts or rivets.

Among the special objects of my invention are to provide efficient means for loosening the plow-share, so that it can be easily removed. In attaching the plow-share to the mold-board, a wedging action is employed to firmly force the same into proper position, and in removing the share this wedging action is first released and then the share moved bodily so as to loosen the same, whereby it may be easily removed. Furthermore, by my invention I provide a suitable quick detachable means for the share without unduly weakening the frog.

These and other features and objects of my invention will be more readily understood by having reference to the accompanying drawings, in which I have illustrated the preferred embodiment of my invention.

Figure 1 is a perspective view of a plow embodying my invention, the plow being shown as resting upon the land-side.

Fig. 2 is a view looking directly at the edge of the plow-share, as shown in Fig. 1, a portion of this plow-share and of the frog

being shown in section to more clearly show the operating parts.

Fig. 3 is a detail view looking directly at the bottom of the plow—that is, a view taken on a plane at right angles to Fig. 2.

Fig. 4 is a front elevation of the plow. 60

Fig. 5 is a sectional view taken on the line 5—5 of Fig. 2.

Fig. 6 is a sectional view taken on the line 6—6 of Fig. 3.

Fig. 7 is a perspective view of the plow-share.

As illustrated, my improved plow comprises the usual mold-board 10 and land-side 11, secured together by the frog 12, the usual strengthening braces 13, 14, being provided between the mold-board and the frog and land-side, respectively. The plow-share 15 is of the usual shape, but instead of being bolted or riveted to the frog, I provide suitable quick detachable means which will now be described.

Mounted on the back of the mold-board, there is a hand-lever 16 which at its forward end is bifurcated so as to form a yoke-shaped member, the arms 17 of this yoke being pivoted on a pair of ears 18 attached to the back of the mold-board. Pivoted in this yoke is a transverse bearing member 19, through which a rod 20 extends, which rod is threaded at its ends and held in position by a pair of lock nuts 21, whereby the rod may be suitably adjusted longitudinally in this bearing member. The opposite end of this rod is pivotally secured to a plate 22, which plate is provided with a longitudinal guiding slot 23 which engages with a bolt 24 carried by the frog 12. This guiding slot insures a straight line reciprocating movement for the rod 20, when the same is operated through the medium of the hand-lever 16. The plate 22 is likewise provided with an opening 25, the ends being rounded and one end being larger than the other, as clearly shown in Fig. 3. This opening 25 in this plate is adapted to register with a somewhat similar shaped opening 26, although reversed in position, in the frog 12.

Secured to the plow-share 15, there is a bolt 27 which carries a sleeve 28, which sleeve is provided with an enlarged head or flange 28. This sleeve is held in position on the bolt 27 by means of the nut 29. The opening 26 in the frog is of sufficient size at its

larger end to permit the flange 28^a to pass freely through the same. This head or flange 28^a likewise passes through the opening 25 in the end of the plate 22, so that the 5 end of this plate grips this sleeve 28 beneath the head or flange 28^a—that is, between this head and the frog. The lower surface of this flange 28^a is cam-shaped—that is, the portion of the flange first engaged by the 10 plate 22 is slightly narrower than the other portions of the flange so that as the plate is operated by the hand-lever, in the manner to be hereinafter described, it operates to draw downward on the bolt 27. This action 15 is assisted by having the surface of the plate 22 which engages with the head 28^a likewise inclined, that is, the plate is thicker at its outer edge than immediately adjacent the opening 25. The opening 25 is so shaped 20 that the end of the plate 22 engages the head or flange 28^a at diametrically opposite points, so that this wedging action produces a pull on opposite sides of the bolt 27, and thus prevents any bending or shearing action on 25 this bolt. The surface of the flange 28^a which engages with the frog 12 is likewise inclined so as to produce a further wedging action as the plate is drawn into locking position.

30 Secured to the plow-share, there is an offset fastening member 30, which is adapted to engage with an extension 31 on the brace 14. The forward end of the frog is cut away, as clearly shown in Figs. 1 and 2, 35 and the share is provided with a pin 32 adapted to engage with this cut-away portion. The edge 33 of this cut-away portion is slightly inclined, so that as the share is drawn into position and the pin rides on 40 this inclined surface, there is a wedging action which tends to firmly force the share into engagement with the frog and mold-board.

The method of attaching and detaching 45 this share is as follows:—The point of the share is first slipped over the end of the frog, so that the pin 32 engages with the inclined surface 33 at the same time the bolt 27 is passed through the enlarged portion of the opening 26 and the hand-lever 50 16 is thrown into the dotted line position shown in Fig. 2, so that this bolt 27 and head 28^a likewise pass through the enlarged portion of the opening 25 in the plate 22. At this time the offset member 30 is in position to engage the member 31, the parts all being shown in the dotted line position 55 of Fig. 2. The hand-lever is then thrown to the left, as shown in Fig. 2, and thus 60 draws the rod 20 and plate 22 to the left, pulling upon the bolt 27 attached to the plow-share. This draws the plow-share from the dotted line position, Fig. 2, into the full line position, and during this movement the pin 32 slides on the inclined sur-

face 33 of the point of the frog, thus drawing the share by a wedging action into proper position against the mold-board. The plate 22 engages beneath the cam surface of the head 28 on the bolt 27, thus pulling down on the share at the same time that the same is drawn to the left, and the offset edge of the member 30 likewise engages with the member 31. This offset edge of the member 31 is likewise slightly inclined 70 so as to create a wedging action. Thus we see that at three points this movement of the hand-lever creates a wedging action on the plow-share, so as to firmly and securely clamp the same in position against the 80 mold-board. By swinging the lever over center—that is, to such a position that the rod 20 passes upon the other side of the pivotal point of the lever 16—the parts are firmly locked in this position. In order to 85 quickly detach the share from the mold-board, it is merely necessary to swing the hand-lever back again to the dotted line position, during which movement the plate 22 moves so as to disengage itself from the 90 head 28, thus relieving the wedging action between this plate and the head of the bolt, and then as the rod 20 is moved still farther to the right, the left-hand end of the opening 25 of this plate strikes the bolt 27 95 so as to give the share a sudden kick to thereby bodily move the same and thus loosen the engagement between the offset member 30 on the share and the member 31 carried by the frog, as well as to loosen the 100 engagement between the pin 31 at the point of the share and the inclined edge 33 of the frog. Thus the movement of the hand-lever in releasing the share not only releases all the means which were locking or holding 105 the share in position against the mold-board, but it likewise gives the share a sudden kick to loosen the plow-share from the mold-board, so that it can be readily removed. It will likewise be seen that by my 110 construction I have provided a plow-share which is readily detachable and yet firmly held in position at three independent points; and, furthermore, the frog has not been unduly weakened by numerous holes 115 and slots, as but a single hole has been made in this frog.

While I have illustrated and described one specific embodiment of my invention, it will be understood that various changes and modifications may be made without departing from the spirit and intent of my invention.

What I claim as my invention is:

1. In a plow, a mold-board, a frog secured thereto, a removable share adapted to be seated against said frog, means for bodily moving said share to lock the same in position against said frog, said means upon release unlocking said share and bodily 125

moving the same to thereby render the same freely removable from said frog.

2. In a plow, a mold-board, a frog secured thereto, a removable share adapted to be seated against said frog, an opening in said frog, a bolt secured to said frog and passing through said opening, and means located on the under side of said frog for engaging said bolt to move the share bodily and to lock the same in position against said frog, said means operating on release to free said locking means and to bodily move said share so that the same may be readily removed from said frog.

3. In a plow, a mold-board, a frog secured thereto, a removable plow share adapted to be seated against said frog, an opening in said frog, a bolt secured to said share and provided with an enlarged head passing through said opening, a locking plate on the under side of said frog and adapted to engage the said head, hand-operated means for reciprocating said plate, the movement of said plate in one direction operating to move said share bodily and lock the same in position against said frog, the movement of the plate in the opposite direction operating to release said locking means and move said share bodily in the opposite direction, whereby the same may be readily removed from said frog.

4. In a plow, a mold-board, a frog secured thereto, a removable plow share adapted to be held in position against said frog at three independent points, and hand-operated means for locking said share in position against said frog, said hand-operated means operating upon release to release said locking means and to bodily move said share, whereby the same may be easily removed from said frog.

5. In a plow, a mold-board, a frog secured thereto, a share adapted to be seated against said frog, an opening in said frog, a bolt provided with an enlarged head secured to said share and adapted to pass through said opening, a locking member on the lower side of said frog adapted to engage said enlarged head, and means for moving said locking member transversely, the engaging faces of said head and locking member being inclined or beveled and diametrically opposite points on said head engaging said locking member whereby the transverse movement of said locking member operates to move said bolt and share downward and transversely to thereby lock said share in position against said share, without producing any bending stress on said bolt.

6. In a plow, a mold-board, a frog secured thereto, a removable share adapted to be seated against said frog, an opening in said frog, a bolt provided with an enlarged head secured to said share and passing through said opening, a plate provided with an elongated

gated opening mounted on the back of said frog and engaging with said head, a reciprocating rod for drawing said plate in one direction to bodily move said share and lock the same in position against said frog, said reciprocating rod when moved in the opposite direction releasing said locking means and moving said share in the opposite direction to thereby render the same freely removable from said frog.

7. In a plow, a mold-board, a frog secured thereto, a removable share adapted to be seated against said frog, an opening in said frog, a bolt provided with an enlarged head passing through said opening, a plate mounted on the back of said frog and provided with an elongated opening, one end of said opening being of sufficient size to permit said head to pass freely through the same, the other end of said opening being smaller than said head, a rod secured to said plate, and a hand-lever pivoted to said mold-board and secured to said rod so as to move said rod to thereby draw said plate into position, whereby the smaller end of said opening engages between said head and the frog to thereby lock said share into position against said frog, the engaging faces between said head and plate being inclined, whereby a wedging action is produced when said plate is moved into locking position to thereby draw said share firmly against said frog.

8. In a plow, a mold-board, a frog secured thereto, a removable share adapted to be seated against said frog, an opening in said frog, a bolt provided with an enlarged head passing through said opening, a plate mounted on the back of said frog and provided with an elongated opening, one end of said opening being of sufficient size to permit said head to pass freely through the same, the other end of said opening being smaller than said head, a rod secured to said plate, a hand-lever pivoted to said mold-board and secured to said rod so as to reciprocate said rod to thereby draw said plate into position, whereby the smaller end of said opening engages between said head and the frog to thereby lock said share into position against said frog, the engaging faces between said head and plate being inclined whereby a wedging action is produced when said plate is moved into locking position to thereby draw said share firmly against said frog, said opening being so shaped that the plate engages said head at diametrically opposite points, thereby eliminating any bending or shearing stress on said bolt when the same is drawn into locking position.

9. In a plow, a mold-board, a frog secured thereto, a removable share adapted to be seated against said frog, adjustable hand-operated means for bodily moving said share to lock the same in position against said frog, said hand-operated means upon release

unlocking said share and bodily moving the same to thereby render the same freely removable from said frog.

10. In a plow, a mold-board, a frog secured thereto, a removable plow share adapted to be seated against said frog, an opening in said frog, a bolt secured to said share and provided with an enlarged head passing through said opening, a locking plate 5 on the under side of said frog and adapted to engage the said head, hand-operated means adjustably connected to said plate for

reciprocating same, the movement of said plate in one direction operating to move said share bodily and lock the same in position 15 against said frog, the movement of the plate in the opposite direction operating to release said locking means and move said share bodily in the opposite direction, whereby the same may be readily removed from said frog. 20

Signed by me at Rock Island, Ill., this 14th day of March, 1919.

LEE H. KAUPKE.
